(57) CLAIM

The ornamental design for a collapsible hanging packing organizer as shown and described.

DESCRIPTION

FIG. 1 is a front perspective view of a collapsible hanging packing organizer, showing my new design;

FIG. 2 is a rear perspective view thereof;

FIG. 3 is a front elevational view thereof;

FIG. 4 is a rear elevational 10 view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the collapsible hanging packing organizer that form no part of the claimed design.

1 Claim, 8 Drawing Sheets
